Attorney

UNITED STATES PATENT OFFICE.

TOKUJI HAYAKAWA, OF TOKYO, JAPAN.

PROPELLED PENCIL.

Application filed July 11, 1923. Serial No. 650,740.

To all whom it may concern:

Be it known that I, TOKUJI HAYAKAWA, a subject of the Emperor of Japan, and a resident of No. 35 Ni-Chome, Hayashi-Cho, Honjo-Ku, Tokyo, Empire of Japan, have invented a new and useful Improvement in Propelling Pencils, of which the following is a specification.

This invention relates to improvement in propelling pencils and particularly to propelling means which is adapted to be contained within the pencil casing or barrel and comprises an inner tube, a spirally grooved guide tube carried within said inner tube and a lead carrier held in said guide tube, so that the lead carrier can be propelled by rotating the guide tube.

An object of the invention is to provide improved connecting means between the inner tube and the guide tube, whereby the use of solder is eliminated and by means of which the assembling and disassembling of the parts for repairs is greatly facilitated, said connecting means serving also to secure the inner tube within the casing.

In the accompanying drawing Figure 1 is a perspective view of the pencil with outer casing in section to disclose the interior thereof.

Figure 2 is a longitudinal section through the assembled pencil.

Figure 3 is a perspective view of the inner tube.

Figure 4 is a perspective view of the clip for connecting the members together.

Figs. 5 and 6 are transverse sectional views taken respectively on the lines V—V and VI—VI of Fig. 2; and

Fig. 7 is a side elevation of the guide tube detached.

In propelling pencils of this kind, the lead carrier is frequently broken and is generally soldered to the inner tube so that both the lead carrier and the inner tube must necessarily be replaced. This invention is designed to eliminate this defect by providing a construction wherein it is necessary to replace only the damaged parts.

It is also a special feature of the invention that the clip serves not only to connect the inner tube with the pencil casing, but also to connect the guide tube carrying detachably the pencil carrier with said inner tube, so that several members of the pencil, which heretofore have been soldered together are made detachable whereby repairs and

inspection can be made with facility, said parts being properly held in their positions.

Referring now particularly to the drawing, 1 designates a pencil casing or barrel which is provided with a conical writing end as usual and is adapted to enclose an inner tube 2.

The inner tube 2 is constructed so as to have three portions having different diameters respectively as shown in Figs. 2 and 3.

The upper portion of the tube 2 is adapted to receive a tube 4 which is attached to an operating head 3, and which tube is in turn adapted to receive the end of a tubular member 14 forming a magazine for the storage of spare leads. The intermediate portion of the tube 2 is provided with a slot 9 and is adapted to receive a guide tube 5, while the lower portion is adapted to receive a lead carrier 8 and allow the same to be propelled.

The guide tube 5 may consist of a tube provided with a spiral groove or may be formed of a tubular coil of spirally wound thin metal strip, so as to provide a spiral guideway. To the rear or upper end of the guide tube 5, is attached by swaging, a connector 7, which is provided with an annular groove 11 approximately in the plane of juncture with the guide tube, which connector is attached by swaging to one end of the magazine tube 14 for the spare leads.

The magazine tube 14 thus attached to the guide tube 5, is adapted to be frictionally engaged by the tube 4 so that said guide tube can be rotated with the operating head. The magazine tube 14 can be formed integral with the guide tube 5, if desired.

The guide tube 5 carries the lead carrier 8 which has a hook formed integral with its upper or rear end said hook being adapted to project through the spiral guideway in the guide tube 5 and into the slot 9 of the tube 2. This construction allows the lead carrier 8 to be propelled in accordance with the rotation of the guide tube 5.

The inner tube 2 is provided with two perforations or notches 10 at diametrically opposite sides of the upper part of the intermediate portion and is connected with the guide tube 5 by the engagement of two legs 13 of a clip 12 with the notches 10 and the annular groove 11 of the member 7, said groove and notches being brought into alignment when said guide tube is inserted into the inner tube.

The clip 12 is made of metal wire which

is first formed into **U** shape and the ends of the two legs then bent over at right angle so that they can be inserted into the annular groove 11 on the connector 7 through the notches 10 in the inner tube 2, the **U**-shaped portion being adapted frictionally to engage the walls of the inner tube and casing, as clearly shown in Fig. 6, thereby to prevent rotation of the tube relative to the casing.

10 Thus the present invention provides a propelling pencil, the lead of which can be propelled by rotation of the operating head.

Having thus described my invention, what I claim is:

15 1. A device of the character described, comprising, in combination, an outer casing, an inner tube within said casing, a guide tube within said inner tube, and a removable clip frictionally engaging said tubes and casing thereby to hold the inner tube against rotation in the casing and to lock the guide tube against longitudinal movement while permitting rotation thereof relative to said inner tube.

20 25 30 35 40 2. A device of the character described, comprising, in combination, an outer casing, an inner tube within said casing and having a pair of diametrically opposite notches in its wall, a guide tube within said inner tube and provided with an annular groove disposed in diametrical alinement with said notches, and a removable clip disposed between and adapted frictionally to engage the walls of said inner tube and casing thereby to prevent rotation of the tube relative to the casing, said clip having a pair of legs projecting through said notches into engagement with said annular groove thereby to lock the guide tube against longitudinal movement while permitting rotation thereof relative to the inner tube.

3. A device of the character described, comprising, in combination, an outer casing, an inner tube within said casing and having a pair of diametrically opposite notches in its wall, a guide tube within said inner tube and provided with an annular groove disposed in diametrical alinement with said notches, and a removable **U**-shaped clip disposed between and adapted frictionally to engage the walls of said inner tube and casing thereby to prevent rotation of the tube relative to the casing, said clip having a pair of legs extending at right angles to the body thereof and projecting through said notches into engagement with said annular groove thereby to lock the guide tube against longitudinal movement while permitting rotation thereof relative to the inner tube.

4. A device of the character described, comprising, in combination, an outer casing, an inner tube within said casing, said inner tube comprising portions of different diameters, one of said portions having a longitudinal extending slot in its wall, a guide tube of spiral formation disposed within said portion and adapted for rotation relative to said inner tube, the coils of the spiral being spaced apart to provide a guideway, a movable lead carrier normally disposed in the portion of the inner tube of smallest diameter and provided with a guide member extending through said guideway and into said slot, means for rotating the guide tube, and removable means for retaining the inner tube against rotation relative to the casing and for holding the guide tube against longitudinal movement while permitting rotation thereof relative to the inner tube.

In testimony whereof I have signed my name to this specification.

TOKUJI HAYAKAWA.
